UNITED STATES PATENT OFFICE.

FRANK ZILKER, OF NEW ORLEANS, LOUISIANA.

CLOSURE OPERATOR.

Application filed January 31, 1922, Serial No. 533,107. Renewed April 2, 1924.

To all whom it may concern:

Be it known that I, FRANK ZILKER, a citizen of the United States, and resident of New Orleans, in the parish of Orleans and State of Louisiana, have invented 5 a new and Improved Closure Operator, of which the following is a full, clear, and exact description.

My invention relates to a closure operator, and aims to provide a device of this 10 character, particularly adapted for use in connection with the closure of receptacles, such as inking pads, etc., although it is not necessarily limited to this particular 15 adaptation.

It is a well appreciated fact, in connection with receptacles of the type specified, that considerable difficulty is experienced, 20 incident to the fact that an operator's fingers are liable to become soiled when the closure of the receptacle is opened, and incident to this fact, as well as to carelessness, an operator quite often leaves the receptacle open, which quickly results in the 25 pad becoming dry, and unfit for further use.

With this in mind, my present invention aims to provide an operator for closures, such as are used in connection with the type 30 of vehicle specified, and by means of which closure operator, the action of opening and closing the receptacle will be greatly simplified, aside from the fact that all liability of the operator's hands becoming soiled will be obviated.

35 A further object of this invention is that of constructing a device of the character stated which may be manufactured at a relatively nominal sum, and which will involve an extremely simple construction, and

40 Still further objects of this invention will become apparent in the annexed specification taken in connection with the drawings, which latter illustrate one practical embodiment of the same, and in which;

45 Figure 1 is a perspective view of a receptacle of the type specified, showing the closure of the same in seated position, it being noted that my improved type of operator is associated with said receptacle.

50 Figure 2 is a plan view of the receptacle shown in Figure 1, but illustrating the closure of the same in open position.

55 Figure 3 is a transverse sectional view taken along the line 3—3 and in the direction of the arrows shown in Figure 2, and

Figure 4 is a view in all respects similar

to Figure 3 with the exception that the closure is shown in seated position as in Figure 1.

In the embodiment illustrated I have 60 shown my invention as associated with an ink pad receptacle, and thus the reference numeral 5 indicates any suitable type of base which serves to support a pad 6, the latter being normally covered by a lid 7, 65 the opening and closing of which is controlled by means of my improved type of operating device.

Referring to the construction of this operating member it will be seen that the same 70 includes a lever 8, which may be rockingly mounted, and have its body disposed within a slot 9 forming a part of the base 5. Also it will be seen that the forward end of this lever extends above the base and terminates 75 in a key 10, so that an operator is readily enabled to depress this end of the lever.

Also, contrary to conventional construction, it will be noted that the lid 7 is provided adjacent its point of hinged connection with the base 5, with a contact plate 11, and this contact plate is in line with the inner or rear end of the lever 8. A pair of fingers 12 and 13 are affixed to the rear end of the lever 8 and are spaced with 80 respect to each other, and the finger 13 preferably has its upper end beveled as at 14, while the upper end of the finger 12 is rounded as at 15.

Thus in operation, it will be understood 85 that the parts are normally in the position shown in Figures 1 and 4 but it will be obvious that upon the key 10 being depressed that the inner end of the lever 8 will be swung upwardly, and the finger 12 90 thereof will bear with its rounded portion 15 against the under face of the contact plate 11, thus initially swinging the cover 7 to the position shown in full lines in Figure 3, and subsequently to the position indicated in dotted lines in this figure, and full 95 lines in Figure 2, it being noted in this connection that when the parts are in this position, the finger 13 will act as a stop 100 for the cover 7, and incident to the beveled 105 upper end 14 thereof, the same will lie flush against the upper face of the cover.

It will be seen when the parts are in this position that a second depression of the key 10 will act to again swing the cover 110 past the vertical, so that the same is free to fall to the position shown in Figures 1

and 4, and thus it will be obvious that all of the objects of this invention are accomplished, it being understood that numerous modifications of structure might readily be resorted to without in the least departing from the scope of my claims, which are:

- 5 1. A closure operator including in combination a hingedly mounted closure, a swingingly mounted lever, the axes of pivoting of said closure and lever being substantially parallel, and means adjacent one of the ends of said lever and capable of contacting with said closure for operating the latter when the lever is swung.
- 10 2. A closure operator including in combination a hingedly mounted closure, a swingingly mounted lever, and means adjacent one of the ends of said lever and capable of contacting with said closure for seating the closure when the lever is swung.
- 15 3. A closure operator including in combination a hingedly mounted closure, a swingingly mounted lever, said lever having angularly disposed portions all arranged in substantially the same plane, and means adjacent one of the ends of said lever and capable of contacting with said closure for opening the closure when the lever is swung.
- 20 4. A closure operator including in combination a hingedly mounted closure, a swingingly mounted lever, and means adjacent one of the ends of said lever and capable of contacting with said closure for seating and opening the closure when the lever is swung.
- 25 5. A closure operator including in combination, a hingedly mounted closure, a swingingly mounted lever, and means adjacent one of the ends of said lever and adapted to engage said closure for opening the latter when the lever is subjected to an initial swinging operation, and seating said closure when said lever is subsequently subjected to a secondary swinging impulse.
- 30 6. A closure operator including in combination a hingedly mounted closure, a swingingly mounted lever, means associated

with said lever and adapted to contact with said closure for opening the latter when the lever is initially depressed, said opening operation serving to return said lever to its normal position, said lever being adapted to subsequently have one of its ends again depressed to effect a seating of said closure, said seating operation also serving to return said lever to its normal position.

7. A closure operator including a hingedly mounted cover, a swingingly mounted lever, and a pair of fingers secured in spaced relationship to one of the ends of said lever, and adapted to co-operate with said lever.

8. A closure operator including a hingedly mounted cover, a swingingly mounted lever, and a pair of fingers secured in spaced relationship adjacent one of the ends of said lever, and a contact plate affixed to said cover, one of said fingers being adapted to co-operate with said plate, the second of said fingers co-operating with one of the faces of said cover.

9. A closure operator including a hingedly mounted cover, a swingingly mounted lever, and a pair of fingers secured in spaced relationship adjacent one of the ends of said lever, and a contact plate affixed to said cover, one of said fingers being adapted to co-operate with said plate, the second of said fingers co-operating with one of the faces of said cover, the first of said fingers being formed with a rounded outer end portion.

10. A closure operator including a hingedly mounted cover, a swingingly mounted lever, and a pair of fingers secured in spaced relationship adjacent one of the ends of said lever, and a contact plate affixed to said cover, one of said fingers being adapted to co-operate with said plate, the second of said fingers co-operating with one of the faces of said cover, the last of said fingers having its outer end beveled.

FRANK ZILKER.
